DESIGN FOR A PIN

Harry M. Osers, New York, N. Y.

Application February 14, 1949, Serial No. 849

Term of patent 3½ years

(Cl. D45—19)

To all whom it may concern:

Be it known that Harry M. Osers, a citizen of United States, residing at 110 West 34th Street, New York, in the county of New York and State of New York, has invented a new, original, and ornamental Design for a Pin, of which the following is a specification, reference being had to the accompanying drawing, forming part thereof.

In the drawing:

Fig. 1 is a front elevational view of a pin showing my new design; and

Fig. 2 is a bottom plan view thereof, the pendant ornamental portion of the chain being omitted for convenience of illustration.

I claim:

The ornamental design for a pin, as shown.
HARRY M. OSERS.
